MEANS FOR REGULATING THE RATE OF
FIRE OF AUTOMATIC FIREARMS

George Ironside, Hartford, Conn., assignor to
Colt's Patent Fire Arms Manufacturing Com-
pany, Hartford, Conn., a corporation of Con-
necticut

Application March 25, 1942, Serial No. 436,164

6 Claims.

(Cl. 89—3)

This invention relates to means for regulating the rate of firing of automatic firearms and more particularly to means for varying said rate of firing.

In automatic firearms constructed only for free, automatic firing and having no means included for regulating the rate of firing thereof, overheating of various parts of the firearms, and particularly the barrel, will usually occur so that some form of cooling means is required in order to enable the gun to be continuously fired for reasonably long periods of time and for other than short bursts of fire. Furthermore, when an automatic firearm fires too rapidly, there is a tendency on the part of the firearm to vibrate in various directions whereby the accuracy of the gun is impaired due to the inability of the operator to hold the firearm sufficiently still to accurately aim it. This tendency of the gun results in wasting ammunition.

It is the object of the present invention to provide in an automatic firearm a retarding means which will produce a rate of fire considerably slower than the rate of fire resulting where no retarding means is used whereby the barrel of the firearm may be cooled by air rather than a water jacket and, due to the slower rate of fire, the accuracy of the firearm is enhanced with the result that waste of ammunition is reduced.

It is a further object of the present invention to provide adjustable mechanism in the retarding means whereby the rate of fire of the firearm may be varied within certain predetermined limits.

These objects of the invention are attained through the provision of improved mechanism, the details of which include an escapement mechanism having a pawl including adjustment means, improved means for guiding some of the various movable parts and the particular arrangement, and construction of the breech bolt engaging means, all of which details and the advantages thereof as well as other objects of the invention will be described with more particularity in the following specification:

The accompanying drawings show the embodiment of the invention which is deemed preferable, but it will be understood that the drawings are intended for illustrative purposes only and are not to be construed as defining or limiting the scope of the invention, the claims forming a part of this specification being relied upon for that purpose.

In the drawings:

Fig. 1 is a side elevation of an automatic firearm including the breech bolt retarding mechanism forming the subject matter of the invention, the breech casing of said firearm being partly broken away to disclose the retarding mechanism.

Fig. 2 is a fragmentary sectional elevation taken on the line 2—2 of Fig. 1 and is on a larger scale than in Fig. 1.

Fig. 3 is a fragmentary side elevation, partly in section, taken on the line 3—3 of Fig. 2 showing details of the retarding mechanism and the breech bolt in fully recoiled position.

Fig. 4 is a side elevation similar to Fig. 3 but showing the breech bolt forward of its position in Fig. 3 and about to be released by the retarding mechanism, the arrow on the breech bolt indicating the direction of travel thereof.

Fig. 5 is a plan view of details of the lock frame and the retarding mechanism and also fragments of other parts in the breech casing with all of the parts in the same relative position as in Fig. 3.

Fig. 6 is a fragmentary side elevation showing the breech bolt in a position during movement in recoil direction as indicated by the arrow, the breech bolt depressing the pawl of the retarding mechanism while so moving.

Fig. 7 is a fragmentary side elevation similar to Fig. 6 but showing the breech bolt in a position during movement in counter-recoil direction as indicated by the arrow, the breech bolt having just engaged the pawl of the retarding mechanism.

Fig. 8 is a side elevation of a combined escapement and ratchet wheel.

Fig. 9 is a front elevation of the combined escapement and ratchet wheel.

Figs. 10, 11 and 12 are respectively rear, side and front elevations of the escapement weight included in the retarding mechanism.

Figs. 13 and 14 are respectively a plan and side elevation of the movable pawl carrying member in the retarding mechanism.

Fig. 15 shows end and side elevations of one member of a separable pin device for guiding the movable member shown in Figs. 13 and 14.

Fig. 16 shows end and side elevations of another member of said separable pin device which cooperates with the member shown in Fig. 15.

Figs. 17 and 18 are respectively a plan view and a side elevation of the adjustable pawl of the retarding mechanism.

Fig. 19 is a fragmentary elevation taken on the line 19—19 of Fig. 7 showing a detail of a portion of the breech bolt.

The subject matter of the present invention primarily relates to retarding mechanism which is adapted to cooperate with the breech bolt of an automatic firearm such as a machine gun. In some respects, the basic principles of the present invention are similar to those embodied in my co-pending application, Ser. No. 385,397, filed March 27, 1941.

Referring to the drawings, the automatic firearm illustrated in the present embodiment as a machine gun is shown at 10. The breech casing 12 contains the conventional cartridge belt feeding mechanism, cover plate, mounting means, back plate, rear handle and trigger mechanism, and other parts and portions of machine guns which are illustrated in detail in other patents such as U. S. Patent 1,293,021 to Browning, and U. S. Patent 1,628,226 to Browning. Reference is made to said patents for an explanation of the details illustrated in the present drawings but not described. It is believed, however, that anyone skilled in the art will readily recognize the function of these details which are illustrated but not described, and since they constitute no part of the present invention it is believed that a description of the same is unnecessary.

Operably included in the breech casing are a reciprocable barrel extension 14 and breech bolt 16, the breech bolt having a depending projection 18 which extends below the lower surface of the remainder of the breech bolt and one of the normal functions thereof is to co-act with the accelerator 20 in a manner similar to that described in above referred to Patent 1,628,226. The breech bolt 16 is reciprocable in the breech casing between full recoil and firing positions. The explosion produced upon firing the cartridge generates the force to move the breech bolt in recoil direction while driving spring 17 forces the breech bolt in counter-recoil direction to firing position. The accelerator 20 also cooperates with the barrel extension projection 22 in a manner similar to that described in said patent. The barrel extension projection 22 has a member 24 extending laterally therefrom at one side for engagement by the barrel plunger 26 which is normally resiliently urged forward by spring 28. When the barrel extension is in retracted or fully recoiled position as shown in Figs. 3 and 4, the accelerator locks the barrel extension in its rear-most position and holds the spring 28 compressed. The barrel plunger 26 has a suitable shaft 30 which is surrounded by the spring 28.

A lock frame generally designated as 32 and comprising side plates 34 and 36 is disposed in the rear portion of the breech casing. Mounted between and united with the side plates is a spacing plate 38 having a suitable aperture through which the spring 28 and shaft 30 project as best shown in Fig. 3. The accelerator 20 is also pivotally mounted between the side plates of the lock frame.

The lock frame 32 carries the entire breech bolt retarding mechanism as a unit. The lock frame is readily removable from the rear of the breech casing, after the back plate assembly has been removed, whereby the accelerator mechanism may be readily removed for any desired purpose such as inspection or for replacement of parts. The conventional side plates of the breech casing 12 are each provided with a longitudinal groove 39 on the inner face thereof whereby a pair of oppositely disposed grooves are provided on the interior of the breech casing to slideably

receive projecting guide lugs 40 which are integral with and project outward from the side plates 34 and 36 of the lock frame. The guide lugs 40 primarily prevent upward or downward transverse movement of the lock frame with respect to the breech casing.

A spacing sleeve 42 is fixed to and disposed between the side plates adjacent the rear end of each. Slideably disposed within and normally spring pressed outward toward one end of said spacing sleeve is a locking plunger 44 which extends through and projects outward beyond the side plate 36. The locking plunger 44 is receivable in a suitable aperture 46 provided in the adjacent side plate of the breech casing to prevent longitudinal movement of the lock frame with respect to the breech casing. The outer end of the locking plunger 44 is therefore adapted to be engaged from the exterior of the breech casing by any suitable tool or implement and pressed inward to free it from the aperture 46 in the side plate of the breech casing following which the lock frame assembly may be removed rearward from the breech casing for the above mentioned purposes.

Also mounted between the side plates of the lock frame and disposed in a suitable notch 48 arranged in the upper portion of the spacing plate 38 is a trigger bar 50 movably mounted on a pivot 52. As shown in Fig. 4, the trigger bar is adapted to be actuated by the trigger 53.

A shoe or pawl carrying member 54 is reciprocably mounted for guided movement between the side plates of the lock frame. The path of said shoe is in a substantially straight line extending forward and downward in the lock frame which directions are with respect to the breech casing in which the barrel end of the breech casing is considered the forward end thereof. The term "downward" is considered with respect to the position of the firearm shown in Fig. 1.

The means producing or controlling the guided movement of the shoe 54 consist of: a pair of apertures 56 provided in the shoe; a pair of slots 58 formed in the side plate 36 with the slots disposed at an angle to the longitudinal edges of the side plate and parallel to each other and also to the line of movement of the shoe; and a pair of guide sleeves or pins 60 which are in the nature of slideable guide bearings and are disposed through the apertures 56 in the shoe and the guide slots 58 in the side plate 36. The guide slots 58 illustrated herein are disposed at an angle of approximately fifteen degrees to the longitudinal edges of the side plate 36. This angle has been found to produce satisfactory results but the same is to be interpreted as descriptive and not restrictive since a variance either way in the angle will produce passable results. Each pin 60 is a composite member formed of a sleeve 62 provided with a head having a counterbored annular shoulder 64 disposed therein and a headed split pin 66 having an enlarged end opposite the head which forms laterally projecting detents 68. By inserting the enlarged end of the split pin 66 in the unheaded end of the sleeve 62, the detents of the split pin will be compressed toward each other until such time as the pin 66 is completely inserted within the sleeve 62 when the detents 68 will clear the interior of the sleeve 62 and move away from each other to engage the annular shoulder 64 of the headed sleeve 62. The outer end 75 of each detent 68 is rounded and tapered, as

well shown in Fig. 16, for purposes of being engaged by a suitable annular tool which may be pressed against the tapered portion of the detents to force them together to clear the annular shoulder 64 of the sleeve 62 to permit the disengagement of the slotted pin 66 from the sleeve 62.

It will thus be seen that the shoe 54 is adapted to be quickly secured to the side plate 36 for reciprocal guided movement with respect thereto and in view of the particular locking means provided in the guide pins 60 for holding the composite parts thereof together, said pins will not become disengaged due to general use, vibration, or jarring incident to the manipulation and operation of the machine gun. However, when it is desired to remove the shoe from the side plate for any purpose desired, the removal of the shoe is readily accomplished due to the quickly detachable nature of the composite guide pins 60.

The width of the slots 58 is adequate to receive the diameter of each of the guide pins 60 without appreciable wobble or looseness in order to eliminate lost motion and consequent chatter incident to the movement of the shoe 54 in operation. Only sufficient clearance is provided, however, to permit smooth sliding movement of the guide pins 60 within the slots 58.

The perimeter of each slot 58 adjacent the outer surface of the side plate 36 is provided with a recessed shoulder 70 which extends uniformly around the perimeter of each slot to accommodate the head of the slotted pin 66 provided on each of the guide pins 60 whereby the outer end of said head is substantially flush with the outer surface of the side plate 36 whereby, when the shoe slides with respect to the side plate, the movement of the pins 60 carried by the shoe will not interfere with the adjacent side plate of the breech casing.

The shoe 54 is provided on its upper surface with an elongated recess 72, which is open on one side of said shoe as shown in Fig. 13, to receive a pivoted pawl to be described. The shoe 54 is also provided adjacent one end with a slot 74 extending longitudinally of the shoe and opening upward and outward toward said end to provide a pair of ears 76 through each of which an aperture 56 extends. A slot or recess 78 is also provided in the shoe 54 in the under side thereof adjacent the opposite end, as best shown in Figs. 4 and 14, to pivotally receive and mount one end of a ratchet rack to be described. The pivot for said rack consists of a pin 80 extending through the side portions of the shoe 54 disposed on opposite sides of the recess 78. The shoe 54 also has a projection 82 extending longitudinally outward from one end thereof which projection provides a surface with which an adjustment screw, to be described, is adapted to engage.

A breech bolt engaging dog or pawl 84 is pivotally mounted on and carried by the shoe 54. The pawl has a central portion 86 reduced in width and containing a bearing aperture 88. The reduced central portion of the pawl is received between the upstanding ears 76 of the shoe 54 and one of the guide pins 60 extends through the apertures 56 in the ears 76 and the bearing aperture 88 of the pawl to pivotally connect the pawl to the shoe. One end of the pawl is formed as a breech bolt engaging portion 90. The upper surface 92 thereof is relatively long and is provided with a smooth finish whereby, when the

breech bolt is moving in recoil direction, it will engage the pawl with a free sliding movement over the upper surface 92 and, in so doing, the movement of the breech bolt will not be encumbered. Also, in view of the relatively large area afforded by upper surface 92, no appreciable amount of wear will take place on this portion of the pawl due to the breech bolt sliding thereover. Furthermore, this breech bolt engaging end of the pawl is hardened, when finished, to a relatively high degree to further resist tendency to wear.

The other end of the pawl has an irregular contour, as shown in Fig. 18 particularly, and is provided with a slot 94 extending inward from the end and terminating in a threaded aperture 96 provided in said end of the pawl to receive a threaded adjustment screw 98 for purposes to be described. The slot 94 provides a pair of extending wings 100, one of which contains a countersunk aperture 102 and the other a threaded aperture 104, which apertures receive a headed locking screw 106 adapted to clamp said wings about the adjustment screw 98, after the same has been adjusted to the desired position, to maintain said adjustment. Adjustment screw 98 is made accessible through the forward slot 58 by removing the lock frame assembly from the breech casing.

The under side of the breech bolt engaging portion or end of the pawl 84 is provided with a circular recess 108 to receive one end of a coil compression spring 110, the other end of which is received in a circular recess 112 in the base of the recess 72 in the shoe 54. The spring 110 normally urges the breech bolt engaging end of the pawl into proper position to engage the breech bolt during a portion of the counter-recoil movement of said breech bolt prior to the return of the latter to full firing position. The upper limit to which the breech bolt engaging portion 90 of the pawl may be elevated is controlled by a stop 114 formed on the under side of the reduced central portion 86 of the pawl which stop is adapted to engage the base of the slot 74 formed in the shoe 54.

It will be observed that disposing the pivot for the pawl forward of the breech bolt engaging portion 90 produces what might be termed a pusher type pawl and the design thereof is such that as the breech bolt pushes against the pawl while moving in counter-recoil direction, the pawl will be urged all the more into engagement with the substantially vertical surface on the breech bolt projection 18 which is engaged by the pawl. With this design, even should the breech bolt engaging portion 90 of the pawl become worn, positive engagement between the projection 18 and the portion 90 of the pawl is still insured, thus resulting in long life for the pawl.

Previous to its engagement by the breech bolt depending projection 18, the pawl 84 projects upward above the upper edges of the lock frame 65 and the upper surface of the shoe 54 as best shown in Figs. 1, 3 and 7. The extent to which the end 90 extends upward depends upon the adjustment of the screw 98. Said screw is of adequate length that when desired, it may be threaded downward into the pawl sufficiently to coact against the projection 82 of the shoe 54 and withdraw the breech bolt engaging end into the recess 72 sufficiently so that it will be completely below the upper surface of the shoe 54 and not engage the breech bolt in its recipro-

cable movement in the breech casing. When in such withdrawn position, the pawl will thus render the retarding mechanism inoperative and the machine gun may then fire at full, or non-retarded, speed.

As is obvious from Fig. 6, the dimensions of the adjustment screw 98 are such that when the breech bolt moves in recoil direction and cams the pawl downward into the recess 72, the upper end of the screw will not interfere with such movement of the breech bolt.

The spacing plate 38 is formed with a block 114 extending forward thereof and containing a circular bearing aperture 116 extending therethrough at an angle to the horizontal and parallel to the slots 58 in the side plate 36. Loosely mounted in a circular recess 118 in the projection 82 of the shoe is a reduced end 120 of a cylindrical shaft 122. The diameter of the reduced end 120 is slightly less than the diameter of the circular recess 118 whereby a small amount of play may take place between the shaft 122 and the shoe 54 for purposes of permitting a certain amount of self-centering of the shaft 122 in the aperture 116. The reduced end 120 is held against removal from the circular recess 118 by a suitable locking pin 124 which extends through the projection 82. Surrounding the shaft 122 is a compression spring 126 which impinges at its opposite ends against a face on the block 114 and the end of the projection 82 to normally resiliently urge the shoe 54, and pawl carried thereby, to its uppermost and rearmost position. The shaft 122 is primarily for the purpose of maintaining the spring 126 in proper alignment and in operative position.

A combined member, having an escapement wheel or gear 128 and a ratchet wheel or gear 130 similar to a pinion gear, is mounted for rotatable movement on a fixed shaft 132 extending between the side plates. In the preferred embodiment of the invention, the combined wheel is formed from a single piece of stock, but it is to be understood that it may be formed in any other manner such as by making the escapement and ratchet wheels separately and suitably securing them for movement in unison. The combined wheel is shown in detail in Figs. 8 and 9.

An escapement weight 134, details of which are shown in the various views in Figs. 10 through 12, is also mounted for oscillatory movement about a fixed shaft 136 extending between the side plates. In order that the size of the breech casing might be maintained at a minimum and yet, to the end that the maximum amount of required weight might be afforded the escapement weight, the latter has been designed with a somewhat irregular configuration, as will be observed from Figs. 10 through 12 especially, in order that the escapement weight may be fitted into the design of the lock frame and be free to move with respect to the remainder of the retarding mechanism included therein. It will be observed, for example, that one weight producing portion 138 is relatively narrow and extends upward and rearward, clearing the spacing sleeve 42, the shoe 54, and the trigger bar 50. Another weight producing portion 140 is wider than portion 138 and also extends rearward, clearing the spacing sleeve 42.

Spaced escapement teeth 142 are arranged on one face of the escapement weight and are adapted to co-act with the teeth of the escapement wheel 128, the spacing of the teeth 142 being

such that an oscillatory movement is produced in the escapement weight as the escapement wheel 128 is moved in a given direction past and into engagement with the escapement teeth 142. The escapement mechanism just referred to comprising the escapement wheel 128 and escapement weight 134 might be termed a retarder device.

It might be said that the portions 138 and 140 10 constitute the main weight producing portions of the escapement weight and it will be noted that these portions, for the most part, extend substantially horizontally when the firearm is in normal firing position whereby the function of the escapement weight is enhanced due to the force of gravity tending to move the escapement in one direction at all times when the firearm is operated in or substantially in the position shown in Fig. 1. The total mass of the escapement weight is sufficient, however, that the function of the escapement mechanism will be satisfactory when the firearm is held in other positions than the one referred to above.

A rack 144 for connecting the escapement mechanism to the shoe 54 is mounted on the shoe for movement therewith in the reciprocatory path of the shoe. The rack, however, is otherwise floatingly mounted with respect to the shoe whereby the rack is free to move within certain limits in a direction substantially transverse to the line of reciprocatory movement of the shoe. The construction permitting this consists of a slot 146 extending inward transversely from one side of the rack at one end thereof. Said slot 30 extends about the pin 80 projecting through the shoe 54 and the recess 78 formed therein, which recess receives the end of the rack containing the slot 146. The face of the rack opposite that having the ratchet teeth is formed with a plurality of circular recesses 148. Similar recesses 150 are formed in the adjacent face of the shoe, the opposed recesses 148 and 150 receiving compression springs 152 therebetween to normally resiliently urge the ratchet teeth of the rack into engagement with the teeth of the ratchet wheel 130.

When the shoe 54 is moving forward and downward due to the guide slots 58 and the action of the breech bolt engaging the pawl 84 when the breech bolt is moving forward in counter-recoil direction, the rack 144 engages the ratchet gear 130 which in turn rotates the escapement wheel 128 and this in turn wobbles or oscillates the escapement weight about its pivot to produce a retarding effect upon the movement of the shoe 54 in the direction described. When the shoe is so moved, the spring 126 is also being compressed.

Upon the release of the forward face of the depending projection 18 of the breech bolt by 60 the pawl 84, the spring 126, being relatively strong, quickly moves the shoe 54 rearward and upward to its normal position of repose. The pawl 84, in the interim, is depressed progressively into the recess 72 of the shoe as long as the shoe 65 continues to move upward and rearward and the depending projection 18 of the breech bolt remains in engagement with the pawl while moving forward thereover in counter-recoil direction. Immediately upon the projection 18 clearing the pawl, the spring 110 will press the end 90 upward. During the upward and rearward movement of the shoe, the springs 152 will yield to 70 permit the rack 144 to ride over the teeth of the ratchet wheel 130 whereby, during the so-called 75 return movement of the shoe, the escapement

mechanism is not actuated except as some possible incidental frictional engagement between the teeth of the rack and the ratchet wheel might actuate the escapement mechanism to a limited extent. The engagement of the pin 80 on the shoe with the slot 146 of the rack insures the positive return of the rack to starting position with the shoe. The slot 146 also permits ready and quick assembly of the rack with the shoe.

A supplementary retarding effect is produced in a further embodiment of the present invention by the provision of a notch 154 in the under face and at one side of the depending projection 18 of the breech bolt, clearly shown in Figs. 7 and 19. After the breech bolt has travelled forward sufficiently in counter-recoil direction to have the projection 18 released by the pawl 84, the spring 126 immediately proceeds to restore the shoe and pawl to starting position. During the continued counter-recoil movement of the projection 18 on the breech bolt, the spring 110 will urge the pawl 84 upward into the recess 154 and the rearmost wall of the notch 154 will promptly be engaged by the pawl 84 to again exert a retarding effect on the breech bolt as it continues to move forward during which continued movement the pawl will again be progressively moved forward and downward until it is out of engagement with the rear wall of the recess 154, following which the breech bolt may continue its forward or counter-recoil movement independently of the retarding effect produced by the escapement mechanism described above and the shoe and pawl will again be restored to their position of repose.

The operation of the retarding mechanism is as follows:

Assuming the breech bolt is forward in firing position and the cartridge has just been fired, the force of the resulting explosion moves the breech bolt and barrel extension rearward until they are disconnected, following which, the accelerator 20 rapidly moves the breech bolt to full recoil position, shown in Fig. 3. The accelerator locks the barrel extension in fully retracted position. The shoe 54 now is in the uppermost and rearmost position shown in Fig. 3. When the projection 18 of the breech bolt moves past the pawl 84 in recoil movement, the pawl will be depressed into the position illustrated in Fig. 6. As soon as the projection 18 has passed over the pawl, the spring 110 restores the pawl to the position shown in Fig. 3. Following the breech bolt reaching full recoil position, the driving spring 17 moves the breech bolt in counter-recoil direction toward firing position and the projection 18 engages the pawl 84 to cause the force or effect of the retarding mechanism to oppose the force of the driving spring 17 to delay the return of the breech bolt to firing position. The initial engagement between the projection 18 and the pawl 84 appears as shown in Fig. 7. With the continued forward movement of the breech bolt projection 18 in counter-recoil direction, the shoe 54 carrying the pawl moves forward and downward and progressively moves the engaging portion 90 of the pawl downward across the substantially vertical face of the projection 18 until the breech bolt and the projection 18 reach the position shown approximately in Fig. 4 wherein the pawl is at the point of releasing the projection 18 to free the same from the effect of the retarding mechanism. During the time the pawl is in engagement with the

projection 18, and is moving forward therewith, the rack 144 is being moved forward and downward by the shoe, the rack rotating the ratchet wheel 130 and simultaneously the escapement wheel 128 wobbles or oscillates the escapement weight and produces a retarding effect or drag on the movement of the shoe in its forward path. Immediately following the disengagement of the pawl from the projection 18, the breech bolt may proceed forward independently of the effect of the escapement mechanism under the influence of the driving spring 17. The projection 18 next engages the accelerator 20 to unlock the barrel extension and permit the spring 28 to urge the barrel extension forward to firing position.

As soon as the pawl has released the breech bolt, the spring 126 immediately begins to restore the shoe 54 to upper and rearmost position shown in Fig. 3. The movement of the shoe upward and rearward while the projection 18 is still moving thereover forces the pawl progressively downward into the recess 72 until the projection 18 has passed thereover, following which, the spring 110 restores the pawl to the position shown in Figs. 1 and 3. During the upward and rearward movement of the shoe 54 the rack resists the force of the springs 152 and rides over the ratchet wheel 130 whereby, under normal circumstances, the escapement mechanism is not actuated during the return movement of the shoe and rack due to which the return of the shoe is more rapid than if the rack only moved in a fixed longitudinal path and did not disengage the escapement mechanism. In addition, the wear on the escapement mechanism is saved during the return movement of the shoe and the rack.

As described in the foregoing, the pawl is provided with adjustment means to permit the varying of the amount of engagement which will take place between the pawl and the projection 18 of the breech bolt. The varying of said engagement will directly affect and control the amount of movement of the breech bolt in counter-recoil direction during which the pawl remains in engagement with the breech bolt. This adjustable or varying function may also be described in terms of a time interval during which the breech bolt is in engagement with the pawl since, obviously, any adjustment in the screw 98 on the pawl will vary the interval of time during which the breech bolt is retarded by the escapement mechanism. The locking screw 106 for the adjustment screw 98 is accessible through the forward slot 58 in the lock frame for manipulation by a screw driver or other suitable tool as is clearly seen from Fig. 1.

When it is desired to further retard or slow down the rate of firing of the machine gun over the retarding afforded by the pawl 84 during one engagement with the breech bolt within the range afforded by the adjustment mechanism of the pawl, one or more notches 154 such as illustrated in Fig. 7 may be formed in the under side of the breech bolt projection 18 to cause the retarding effect of the escapement mechanism to be reacted against the breech bolt and the force of the driving spring 17 a plurality of times. Thus the amount of retarding which may be produced or included in a machine gun by the mechanism illustrated and described in this application has a relatively wide range.

It will thus be seen that the mechanism included in the present invention includes, among other beneficial and improved features, a retard-

ing mechanism having a relatively wide range of adjustability, guide means for certain movable parts of the retarding mechanism which effectively align said parts during movement thereof, a distinctively designed escapement weight adapted to produce a maximum of effect in the space allotted, a floating rack to connect the effect of the escapement mechanism to the breech bolt in one direction of movement of the rack but disconnectible from the escapement mechanism during the return or idling movement of the rack, and the pivotal arrangement of the breech bolt engaging pawl provides a pusher type pawl which will insure positive engagement of the breech bolt by the pawl even though a certain amount of wearing of the pawl takes place.

While the invention has been illustrated and described in its preferred embodiment and has included certain details, it should be understood that the invention is not to be limited to the precise details herein illustrated and described since the same may be carried out in other ways, falling within the scope of the invention as claimed.

What I claim is:

1. In combination with an automatic firearm including a breech casing containing a lock frame and a recoil-actuated breech bolt reciprocable above said lock frame in recoil and counter-recoil directions and said firearm also including means normally urging said breech bolt in counter-recoil direction, mechanism for controlling the rate of firing of said firearm and comprising, retarding means mounted within said lock frame, a member mounted within said lock frame for movement in opposite directions along a fixed path extending forward and downward, said member being connected to said retarding means, a pawl pivotally carried by said member and having a portion extending rearward of the pivot therefor and normally projecting above said lock frame whereby said portion is arranged to engage said breech bolt during the initial part of its counter-recoil movement to effect connection between the breech bolt and said retarding means to oppose the force of the means normally urging the breech bolt in counter-recoil direction and retard the movement of said breech bolt in said direction, said pawl automatically disengaging said breech bolt at a predetermined position in the path of movement of the breech bolt in counter-recoil direction, and a screw adjustably carried by said pawl forward of the pivot therefor and arranged to engage said member to selectively vary the amount said portion of said pawl may pivotally move and project above said lock frame to thereby vary said position at which the pawl automatically disengages said breech bolt.

2. In combination with an automatic firearm including a breech casing containing a lock frame and a recoil-actuated breech bolt reciprocable above said lock frame in recoil and counter-recoil directions and said firearm also including means normally urging said breech bolt in counter-recoil direction, mechanism for controlling the rate of firing of said firearm and comprising, retarding means mounted within said lock frame, a member mounted within said lock frame for movement in opposite directions along a fixed path extending forward and downward, said member being connected to said retarding means, a pawl pivotally carried by said member and having a portion normally projecting above said lock frame in position to engage said breech bolt during the initial part of its counter-recoil movement to effect connection between the

breech bolt and said retarding means to oppose the force of the means normally urging the breech bolt in counter-recoil direction and thereby retard the movement of said breech bolt in said direction, said pawl automatically disengaging said breech bolt at a predetermined position in the path of movement of the breech bolt in counter-recoil direction, a screw adjustably carried by said pawl and arranged to engage said member to selectively vary the amount said portion thereof may pivotally move and project above said lock frame to thereby vary said position at which the pawl automatically disengages said breech bolt, and locking means also carried by said pawl and arranged to lock said screw in any selected position.

3. In combination with an automatic firearm including a breech casing containing a lock frame and a recoil-actuated breech bolt reciprocable above said lock frame in recoil and counter-recoil directions and said firearm also including means normally urging said breech bolt in counter-recoil direction, mechanism for controlling the rate of firing of said firearm and comprising, retarding means mounted within said lock frame, a member mounted within said lock frame for movement in opposite directions along a fixed path extending forward and downward, said member being connected to said retarding means, a pawl pivotally carried by said member and having a portion normally projecting above said lock frame in position to engage said breech bolt during the initial part of its counter-recoil movement to effect connection between the breech bolt and said retarding means to oppose the force of the means normally urging the breech bolt in counter-recoil direction and thereby retard the movement of said breech bolt in said direction, said pawl having a split threaded bearing and arranged to automatically disengage said breech bolt at a predetermined position in the path of movement of the breech bolt in counter-recoil direction, a screw adjustably carried by said split bearing of said pawl and arranged to engage said member to selectively vary the amount said portion thereof may pivotally move and project above said lock frame to thereby vary said position at which the pawl automatically disengages said breech bolt, and a locking screw also carried by said pawl and arranged to tighten said split bearing around said adjustment screw to lock the same in any selected position.

4. In combination with an automatic firearm including a breech casing having a lock frame therein composed of a plurality of members and a breech bolt mounted for reciprocating movement longitudinally of said breech casing and also means normally urging the breech bolt in counter-recoil direction, retarding mechanism mounted in said lock frame and including a member reciprocably movable in a path disposed at an angle to the path of movement of said breech bolt, means for guiding said movable member with respect to one member of said lock frame comprising a plurality of slots arranged parallel to each other and to the path of movement of said movable member and disposed in one of said members and pins mounted on the other of said members and slidable in said slots, for maintaining and guiding the movable member in its path, and means also carried by said movable member and adapted to engage said breech bolt during part of the counter-recoil movement thereof to cause the retarding effect of the retarding mechanism to oppose the

force of the means normally urging the breech bolt in counter-recoil direction and subsequently release the breech bolt at a predetermined position in the path of counter-recoil movement to permit the breech bolt to complete its counter-recoil movement independently of said retarding mechanism whereby a retarded rate of fire is produced in said firearm.

5. In combination with an automobile firearm including a breech casing having a lock frame therein composed of a plurality of members and a breech bolt mounted for reciprocable movement longitudinally of said breech casing and also means normally urging the breech bolt in counter-recoil direction, retarding mechanism mounted in said lock frame and including a member reciprocably movable in a path disposed at an angle to the path of movement of said breech bolt, means for guiding said movable member with respect to one member of said lock frame comprising a plurality of slots disposed parallel to each other and to the path of movement of said movable member and disposed in one of said members and pins mounted on the other of said members and having heads at one end and removable heads attachable to the other end by snap-acting quick detachable means, said pins being slideably disposed in said slots for maintaining and guiding the movable member in its path and means also carried by said movable member and adapted to engage said breech bolt to move therewith during part of the counter-recoil movement thereof to cause the retarding effect of the retarding mechanism to oppose the force of the means normally urging the breech bolt in counter-recoil direction and

subsequently release the breech bolt at a predetermined position in the path of counter-recoil movement to permit the breech bolt to complete its counter-recoil movement independently of said retarding mechanism whereby the retarding mechanism produces a retarded rate of fire in the firearm.

6. In combination with an automatic firearm including a breech casing and a breech bolt having a plurality of longitudinally spaced pawl engaging portions thereon and said firearm also having means normally urging the breech bolt in counter-recoil direction, a retarding mechanism including means longitudinally reciprocable in a path extending forward and downward in said breech casing and a member pivotally mounted on said means and normally resiliently urged into position wherein it is adapted to successively engage said pawl engaging portions of said breech bolt to successively connect said movable means to said breech bolt for movement therewith during a part of the counter-recoil movement of said breech bolt to oppose the force of the means normally urging the breech bolt in counter-recoil direction a plurality of times and subsequently release the breech bolt after each of said engagements at predetermined positions in the path of counter-recoil movement of said breech bolt to permit said breech bolt to complete its counter-recoil movement independently of said retarding mechanism after final release therefrom, whereby the retarding mechanism produces a retarded rate of firing in said firearm.
